[57] CLAIM

The ornamental design for a kettle handle, as shown and described.

DESCRIPTION

FIG. 1 is a side top perspective view of a kettle handle showing our new design;

FIG. 2 is a left side view thereof, the right side view thereof being a mirror image of the left side view thereof;

FIG. 3 is a front view thereof;

FIG. 4 is a rear view thereof; and,

FIG. 5 is a top view thereof.

The broken line showing of a kettle base is for illustrative purposes only and forms no part of the claimed design.
